VARIABLE RESISTOR

CROSS REFERENCE TO RELATED APPLICATIONS

This application is a national stage of International Patent Application No. PCT/JP2021/012693 and claims priority to Japanese Patent Application No. 2020-071142 filed on Apr. 10, 2020. The contents of these priority applications are incorporated herein by reference and regarded as a part of the description of this specification.

TECHNICAL FIELD

The present invention relates to a variable resistor.

BACKGROUND

Conventional variable resistor includes a first wiring board on which a first resistor layer is disposed, a second wiring board on which a current passage layer is disposed so that the current passage layer faces the first resistor layer, and a spacer supporting the first and second wiring boards in parallel spaced apart at predetermined intervals, a pushing operation is applied by a pusher from the outer surface of the second wiring board at any position along the longitudinal direction of the first resistor layer, and the circuit resistance length is arbitrarily set by partially contacting the first resistor layer and the current passage layer (see, for example, Patent document 1).

PATENT DOCUMENT

Patent document 1: JP 2010-146802 A

In the above-mentioned variable resistor, since the pusher is slid in a state where the first resistor layer and the current passage layer directly contact each other, the first resistor layer may be worn and conduction failure may occur.

One or more embodiments of the present invention provide a variable resistor capable of suppressing the occurrence of conduction failure.

SUMMARY

[1] A variable resistor according to one or more embodiments of the present invention is a variable resistor including: a first substrate having a first main surface; a resistor disposed on the first main surface; a first wiring pattern disposed on the first main surface and connected to the resistor; a spacer having an opening; a second substrate having second and third main surfaces and laid on the first substrate via the spacer so that the second main surface is opposed to the first main surface; a connecting body disposed on the second main surface so that the connecting body is in the opening, the connection body being electrically connected to the resistor by pushing of a pusher from the third main surface; and a second wiring pattern disposed on the first main surface and electrically connected to the connecting body by pushing of the pusher, or disposed on the second main surface and connected to the connecting body; in which, in a plan view, the connecting body has a non-overlap region that does not overlap with the resistor, in a plan view, a pushing region in which the pusher can push is included in the non-overlap region, and a resistance value between the first wiring pattern and the second wiring pattern is changed based on a pushing position of the pusher.

2

[2] In one or more embodiments, the second wiring pattern may be disposed on the first main surface and may be arranged to be spaced apart from the resistor, in plan view, the connecting body may partially overlap with the resistor and may partially overlap with the second wiring pattern, in plan view, the pushing region may be set between the resistor and the second wiring pattern, and the connecting body may contact the resistor and the second wiring pattern by pushing of the pusher from the third main surface.

[3] In one or more embodiments, in plan view, one edge of the connecting body may overlap with the resistor over a whole area of the connecting body along the extending direction of the resistor, and in plan view, another edge of the connecting body may overlap with the second wiring pattern over a whole area of the connecting body along the extending direction of the resistor.

[4] In one or more embodiments, the variable resistor may further include first comb tooth patterns disposed on the first main surface and connected to the resistor, in plan view, the first comb tooth patterns may overlap with the pushing region, and a material of which the resistor is made may have an electrical resistivity higher than an electrical resistivity of a material of which the first comb tooth patterns are made.

[5] In one or more embodiments, the second wiring pattern may be disposed on the first main surface, the variable resistor may further include second comb tooth patterns disposed on the first main surface and connected to the second wiring pattern, in plan view, the second comb tooth patterns may overlap with the pushing region, a material of which the resistor is made may have an electrical resistivity higher than an electrical resistivity of a material of which the second comb tooth patterns are made, and the connecting body may contact the first comb tooth pattern and the second comb tooth pattern by pushing of the pusher from the third main surface.

[6] In one or more embodiments, the variable resistor may further include the pusher, the first comb tooth patterns and the second comb tooth patterns may be arranged alternately and substantially at equal intervals along an extending direction of the connecting body in the pushing region, and a pushing portion of the pusher that contacts the third surface may have a dimension larger than a pitch of the first comb tooth patterns adjacent to each other via the second comb tooth pattern in a direction in which the first and second comb tooth patterns are arranged.

[7] In one or more embodiments, the second wiring pattern may be disposed on the first main surface, in plan view, the connecting body may partially overlap with the second wiring pattern, and the connecting body may contact the first comb tooth patterns and the second wiring pattern by pushing of the pusher from the third main surface.

[8] In one or more embodiments, in plan view, an edge of the connecting body may overlap with the second wiring pattern over a whole area of the connecting body along the extending direction of the resistor.

[9] In one or more embodiments, the second wiring pattern may be disposed on the second main surface and may be connected to the connecting body, the connecting body may contact the first comb tooth pattern by pushing of the pusher from the third main surface.

[10] In one or more embodiments, the variable resistor may further include the pusher, the first comb tooth patterns may be arranged substantially at equal intervals along an extending direction of the connecting body in the pushing region, and a pushing portion of the pusher that contacts the third surface may have a dimension larger than a pitch of the

first comb tooth patterns adjacent to each other in a direction in which the first comb tooth patterns are arranged.

[11] In one or more embodiments, the variable resistor may further include: a third wiring pattern connected to the resistor; a third comb tooth pattern connected to the first wiring pattern; and a fourth comb tooth pattern connected to the third wiring pattern, and, in a plan view, the third and fourth comb tooth patterns may overlap with the pushing region.

[12] In one or more embodiments, the spacer may cover a whole of the resistor.

[13] In one or more embodiments, the variable resistor may further include a resin layer covering at least a part of the resistor, and at least one of the resin layer and the spacer may cover a whole of the resistor.

[14] In one or more embodiments, the variable resistor may further include the pusher, and the resistor may have a width narrower than a width of a pushing portion of the pusher that contacts the third main surface.

[15] In one or more embodiments, the resistor may be formed by printing and curing a carbon paste.

[16] In one or more embodiments, the second wiring pattern may include: a first main body disposed on the first or second main surface, and a first protective layer covering a region of the first main body corresponding to the resistor, and a material of which the resistor is made may have an electrical resistivity higher than an electrical resistivity of a material of which the first main body is made.

[17] In one or more embodiments, the connecting body may include: a second main body disposed on the second main surface, and a second protective layer covering the second main body, and a material of which the resistor is made may have an electrical resistivity higher than an electrical resistivity of a material of which the second main body is made.

[18] In one or more embodiments, the variable resistor may further include a third wiring pattern disposed on the first main surface, one end of the resistor may cover an end of the first wiring pattern, another end of the resistor may cover an end of the third wiring pattern, and a material of which the resistor is made may have an electrical resistivity higher than an electrical resistivity of a material of which the third wiring pattern body is made.

[19] In one or more embodiments, the first and third wiring patterns may apply a predetermined voltage to the resistor, and the second wiring pattern may output a voltage based on the pushing position of the pusher.

[20] In one or more embodiments, the variable resistor may further include the pusher, and the pusher may be able to push the third main surface at an arbitrary position along an extending direction of the connecting body.

[21] In one or more embodiments, the variable resistor may further include the pusher, and the pusher may be a slider that can slide along an extending direction of the resistor while pushing the third main surface.

According to one or more embodiments of the present invention, in a plan view, the connecting body has a non-overlap region that does not overlap with the resistor, and the pushing region in which the pusher can push is included in the non-overlap region. Therefore, it is possible to suppress the wear of the resistor due to the sliding of the pusher, and it is possible to suppress the occurrence of conduction failure of the variable resistor.

BRIEF DESCRIPTION OF DRAWINGS

FIG. 1 is a plan view showing the variable resistor according to one or more embodiments of the present invention.

FIG. 2 is a cross-sectional view taken along the line II-II line of FIG. 1.

FIG. 3 is a cross-sectional view taken along the line III-III line of FIG. 1.

FIG. 4 is a cross-sectional view taken along the line IV-IV of FIG. 1.

FIG. 5 is a cross-sectional view taken along the line V-V in FIG. 1.

FIG. 6 is a plan view showing the lower membrane board according to one or more embodiments of the present invention.

FIG. 7 is a bottom view showing the spacer and the upper membrane board according to one or more embodiments of the present invention.

FIG. 8 is a plan view showing the variable resistor according to one or more embodiments of the present invention.

FIG. 9 is a cross-sectional view showing the line IX-IX of FIG. 8.

FIG. 10 is a cross-sectional view taken along the line X-X of FIG. 8.

FIG. 11 is a plan view showing the lower membrane board according to one or more embodiments of the present invention.

FIG. 12 is a bottom view showing the spacer and the upper membrane board according to one or more embodiments of the present invention.

FIG. 13 is a plan view showing the variable resistor according to one or more embodiments of the present invention.

FIG. 14 is a plan view showing the variable resistor according to one or more embodiments of the present invention.

FIG. 15 is a cross-sectional view taken along the line XV-XV of FIG. 14.

FIG. 16 is a bottom view illustrating the spacer and the upper membrane board according to one or more embodiments of the present invention.

FIG. 17 is a plan view showing the variable resistor according to one or more embodiments of the present invention.

DETAILED DESCRIPTION

Embodiments of the present invention will be described below with reference to the drawings.

FIG. 1 is a plan view showing the variable resistor according to one or more embodiments of the present invention, FIG. 2 is a cross-sectional view taken along the line II-II line of FIG. 1, FIG. 3 is a cross-sectional view taken along the line III-III line of FIG. 1, FIG. 4 is a cross-sectional view taken along the line IV-IV of FIG. 1, and FIG. 5 is a cross-sectional view taken along the line V-V in FIG. Further, FIG. 6 is a plan view showing the lower membrane board according to one or more embodiments of the present invention, and FIG. 7 is a bottom view showing the spacer and the upper membrane board according to one or more embodiments of the present invention.

As shown FIGS. 1 to 5, the variable resistor 1A of one or more embodiments includes a lower membrane board 10, an upper membrane board 60, a spacer 90, and a slider 100. The variable resistor 1A in one or more embodiments corresponds to an example of the “variable resistor” in the present invention, the spacer 90 in one or more embodiments corresponds to an example of the “spacer” in the present

invention, and the slider 100 in one or more embodiments corresponds to an example of the “pusher” in the present invention.

The lower membrane board 10 includes a resistor 40 and a wiring pattern 50. On the other hand, the upper membrane board 60 includes a connecting body 80 that electrically connects the resistor 40 and the wiring pattern 50. These membrane board 10, 60 are laminated via a spacer 90, and the spacer 90 ensures a space between the membrane board 10, 60. The slider 100 is configured to slide while pushing on the upper membrane board 60. The resistor 40 and the wiring pattern 50 are electrically connected via the connecting body 80 by pushing of the slider 100.

Further, in the variable resistor 1A, the slider 100 slides while pushing the upper membrane board 60 to change the connection position between the connecting body 80 and the resistor 40, and it is possible to change the resistance length (the resistance value) of the resistor 40. Such applications of the variable resistor 1A, for example, variable resistor elements, position sensors, switches, encoders or the like can be exemplified. The application of the variable resistor 1 of one or more embodiments is not particularly limited to the above.

Hereinafter, the configuration of the variable resistor 1A of one or more embodiments will be described in detail.

As shown in FIG. 6, the lower membrane board 10 is a wiring board including a substrate 20, wiring patterns 31 and 35, a resistor 40, and a wiring pattern 50.

The substrate 20 in the present embodiment corresponds to an example of the “first substrate” in one or more embodiments of the present invention, and the resistor 40 in r corresponds to an example of the “resistor” in one or more embodiments of the present invention, and the wiring pattern 50 in the above corresponds to an example of the “second wiring pattern” in one or more embodiments of the present invention. Further, the wiring pattern 31 in the present embodiment corresponds to an example of the “first wiring pattern” in one or more embodiments of the present invention, and the wiring pattern 35 in the present embodiment corresponds to an example of the “third wiring pattern” in one or more embodiments of the present invention.

The substrate 20 is a film-like member made of a material having flexibility and electrical insulation. As the material constituting the substrate 20, for example, a resin material or the like can be exemplified, and more specifically, polyethylene terephthalate (PET) or polyethylene naphthalate (PEN) can be exemplified. The substrate 20 may not have flexibility.

The wiring patterns 31 and 35 are formed by printing a conductive paste on the upper surface 21 of the substrate 20 and solidifying (curing) the conductive paste. The conductive paste is constituted by mixing conductive particles and a binder resin with water or a solvent and various additives. The conductive paste constituting the wiring patterns 31 and 35 is a low resistance conductive paste having a relatively small electric resistance value. The method of forming the wiring patterns 31 and 35 is not particularly limited to the above. For example, instead of the conductive paste, the wiring patterns 31 and 35 may be formed by etching the metal foil.

As specific examples of the conductive material, silver, copper, nickel, tin, bismuth, zinc, indium, palladium and alloys thereof can be exemplified. As specific examples of the binder resin, acrylic resin, polyester resin, epoxy resin, vinyl resin, urethane resin, phenol resin, polyimide resin, silicone resin, fluororesin, or the like can be exemplified. As the solvent contained in the conductive paste, α -terpineol,

butyl carbitol acetate, butyl carbitol, 1-decanol, butyl cell solve, diethylene glycol monoethyl ether acetate, and tetradecane, or the like can be exemplified.

Although not particularly limited, in one or more embodiments, as the low-resistance conductive paste, a silver paste containing silver as the main component of the conductive particles, or a copper paste containing copper as the main component of the conductive particles is used. As a conductive material, a metal salt may be used. As the metal salt, salts of the above-mentioned metals can be exemplified. The binder resin may be omitted from the above-mentioned conductive paste. Instead of the above-mentioned conductive paste, conductive ink may be used.

Although not particularly limited, either a contact coating method or a non-contact coating method may be used as the method for applying the conductive paste. As specific examples of the contact coating method, screen printing, gravure printing, offset printing, gravure offset printing, flexographic printing, or the like can be exemplified. On the other hand, as specific examples of the non-contact coating method, ink jet printing, spray coating, dispensing coating, jet dispensing, or the like can be exemplified. Although not particularly limited, as the heat source for curing the conductive paste, an electrothermal oven, an infrared oven, a far infrared oven (IR), a near infrared oven (NIR), a laser irradiation apparatus, or the like can be exemplified, and the heat source may be a heat treatment that combines these.

One wiring pattern 31 includes an extending portion 32 extending along the -X direction of the figure, and a wide portion 33 disposed at the end of the extending portion 32. The extending portion 32 and the wide portion 33 are integrally formed by printing the above-mentioned conductive paste on the upper surface 21 of the substrate 20 and curing the conductive paste. The wide portion 33 has a width wider than the width of the extending portion 32. As will be described later, the wide portion 33 is covered with the resistor 40.

Similarly, the other wiring pattern 35 also includes an extending portion 36 extending along the +X direction of the figure, and a wide portion 37 disposed at the end of the extending portion 36. The extending portion 36 and the wide portion 37 are integrally formed by printing the above-mentioned conductive paste on the upper surface 21 of the substrate 20 and curing the conductive paste. The wide portion 37 has a width wider than the width of the extending portion 36. As will be described later, the wide portion 37 is covered with the resistor 40. As long as the planar shape of the extending portions 32 and 36 of the wiring patterns 31 and 35 is linear, the planar shape is not limited to the straight linear shape as described above.

The wide portion 33 of one wiring pattern 31 and the wide portion 37 of the other wiring pattern 35 are arranged apart from each other along the X direction of the figure. The resistor 40 is disposed between the wide portions 33 and 37 and extends along the X direction of the figure. Similarly to the above-mentioned wiring patterns 31 and 35, the resistor 40 is also formed by printing a conductive paste on the upper surface 21 of the substrate 20 and curing the conductive paste.

The conductive paste constituting the resistor 40 is a high-resistance conductive paste having a high electrical resistance value as compared with the above-mentioned low-resistance conductive paste. The conductive paste constituting the resistor 40 contains conductive particles having an electrical resistivity higher than the electrical resistivity of the conductive particles of the conductive paste constituting the above-mentioned wiring patterns 31 and 35. That

is, the resistor **40** is made of a material having the higher electrical resistivity than the electrical resistivity of the material constituting the wiring patterns **31** and **35**, and the resistance value of the resistor **40** is sufficiently higher than the resistance value of the wiring patterns **31** and **35** to the extent that the resistance value of the wiring patterns **31** and **35** can be ignored. Specifically, the resistance value of the resistor **40** is 10 times or more with respect to the resistance value of the wiring patterns **31** and **35**, and may be 100 times or more with respect to the resistance value of the wiring patterns **31** and **35**. The electrical resistivity of the material constituting the resistor **40** is 10 times or more, and may be 100 times or more, with respect to the electrical resistivity of the material constituting the wiring patterns **31** and **35**.

As a specific example of such a high-resistance conductive paste, a carbon paste can be exemplified. As specific examples of the conductive particles contained in the conductive paste constituting the resistor **40**, carbon-based materials such as graphite, carbon black (furnace black, acetylene black, Ketjenblack® (high conductive carbon black)), carbon nanotubes, carbon nanofibers, or the likes can be exemplified.

As described above, the resistor **40** covers the wide portion **33** of one wiring pattern **31** and covers the wide portion **37** of the other wiring pattern **35**. The wiring patterns **31** and **35** are connected to each other by the resistor **40**. Although not particularly shown, one wiring pattern **31** is connected to the power supply, while the other wiring pattern **35** is connected to the ground.

The wiring pattern **50** includes a first main body **51** and a first protective layer **52**.

The first main body **51** is disposed on the upper surface **21** of the substrate **20**. Similarly to the above-mentioned wiring patterns **31** and **35**, the first main body **51** is formed by printing and curing the low-resistance conductive paste. That is, the first main body **51** is made of a material having the lower electrical resistivity than the electrical resistivity of the material constituting the resistor **40**, and the resistance value of the resistor **40** is sufficiently higher than the resistance value of the first main body **51** to the extent that the resistance value of the first main body **51** can be ignored. Specifically, the resistance value of the resistor **40** is 10 times or more with respect to the resistance value of the first main body **51**, and may be 100 times or more with respect to the resistance value of the first main body **51**. The electrical resistivity of the material constituting the resistor **40** is 10 times or more, and may be 100 times or more, with respect to the electrical resistivity of the material constituting the first main body **51**. The method of forming the first main body **51** is not particularly limited to the above. For example, instead of the conductive paste, the first main body **51** may be formed by etching the metal foil.

The first main body **51** extends along the X direction of the figure. The first main body **51** has a parallel portion **511** extending substantially parallel to the resistor **40** at its end. The planar shape of the first main body **51** is not particularly limited to the above.

The first protective layer **52** of the wiring pattern **50** is disposed on the upper surface **21** of the substrate **20** so that the first protective layer **52** covers the parallel portion **511** of the first main body **51**. The first protective layer **52** is a layer that protects the parallel portion **511** of the first main body **51**, and the first protective layer **52** is formed by printing and curing the high-resistance conductive paste. Although not particularly limited, as a specific example of such a high-

resistance conductive paste, carbon paste can be exemplified. The first protective layer **52** has a length similar to the length of the resistor **40** along the X direction of the figure and is arranged at a predetermined distance **D** (see FIG. 6) from the resistor **40**. That is, the first protective layer **52** of the wiring pattern **50** is arranged substantially parallel to the resistor **40**. The wiring pattern **50** may not include the first protective layer **52**.

As shown in FIG. 7, the second membrane board **60** is a wiring board including a substrate **70** and a connecting body **80**. The substrate **70** in the present embodiment corresponds to an example of the “second substrate” in one or more embodiments of the present invention, and the connecting body **80** in the present embodiment corresponds to an example of the “connecting body” in one or more embodiments of the present invention.

Similarly to the above-mentioned substrate **20**, the substrate **70** is a film-like member made of a material having flexibility and electrical insulation. As the material constituting the substrate **70**, for example, a resin material or the like can be exemplified, and more specifically, polyethylene terephthalate (PET) or polyethylene naphthalate (PEN) can be exemplified. The material constituting the substrate **70** is not particularly limited to the above. The substrate **70** may be formed of a plate material made of a conductive material such as a metal material. In this case, the substrate **70** may also function as the connecting body **80**. Further, when the wiring pattern **50** is formed on the substrate **70** as in one or more embodiments described later, the substrate **70** may also function as the wiring pattern **50**. Even when the substrate **70** is formed of a plate material having conductivity, the connecting body **80** and the wiring pattern **50** may be formed on the substrate **70** separately from the substrate **70**.

Similarly to the above-mentioned wiring pattern **50**, the connecting body **80** includes a second main body **81** and a second protective layer **82**. The connection body **80** may not include the second protective layer **82**.

The second main body **81** is disposed on the lower surface **71** of the substrate **70**. Similarly to the above-mentioned first main body **51** of the wiring pattern **50**, the second main body **81** is formed by printing and curing the low-resistance conductive paste. That is, the second main body **81** is made of a material having the lower electrical resistivity than the electrical resistivity of the material constituting the resistor **40**, and the resistance value of the resistor **40** is sufficiently higher than the resistance value of the second main body **81** to the extent that the resistance value of the second main body **81** can be ignored. Specifically, the resistance value of the resistor **40** is 10 times or more with respect to the resistance value of the second main body **81**, and may be 100 times or more with respect to the resistance value of the second main body **81**. The electrical resistivity of the material constituting the resistor **40** is 10 times or more, and may be 100 times or more, with respect to the electrical resistivity of the material constituting the second main body **81**.

On the other hand, the second protective layer **82** is a layer that protects the second main body **81**. Similarly to the above-mentioned first protective layer **52** of the wiring pattern **50**, the second protective layer **82** is formed by printing and curing the high-resistance conductive paste. The second protective layer **82** is disposed on the lower surface **71** of the substrate **70** so that the protective layer **82** covers the entire of the second main body **81**.

As shown in FIG. 1, the connecting body **80** is disposed on the lower surface **71** of the substrate **70** so that the connecting body **80** partially overlaps with the resistor **40** of

the lower membrane board **10** and partially overlaps with the wiring pattern **50** of the lower membrane board **10** in plan view. More specifically, in one or more embodiments, the connecting body **80** has a rectangular planar shape having a width wider than the interval **D**. Then, the connecting body **80** is disposed on the lower surface **71** of the substrate **70** so that one edge (-Y side edge along the X direction of the FIG. **80a** of the connecting body **80** overlaps with the resistor **40** and the other edge (+Y side edge along the X direction of the FIG. **80b** of the connecting body **80** overlaps with the wiring pattern **50** in plan view.

Similarly to the above-mentioned substrate **20** and **70**, the spacer **90** is a film-like member made of a material having flexibility and electrical insulation. As the material constituting the spacer **90**, for example, a resin material or the like can be exemplified, and more specifically, polyethylene terephthalate (PET) or polyethylene naphthalate (PEN) can be exemplified.

As shown in FIGS. 1 to 5 and 7, the spacer **90** has an opening **91** having a rectangular planar shape. The opening **91** has a size that is larger than the connecting body **80** and can accommodate the connecting body **80**. In one or more embodiments, the opening **91** has a size that can accommodate not only the connecting body **80** but also the resistor **40** and the wiring pattern **50**. The opening **91** is formed in the spacer **90** so that the opening **91** accommodates the connecting body **80**, the resistor **40**, and the wiring pattern **50** when the membrane board **10** and **60** are laminated on each other via the spacer **90**. As long as at least a part of the connecting body **80** is inside the opening **91** of the spacer **90**, a part of the connecting body **80** may extend to the outside of the opening **91** and may be interposed between the spacer **90** and the substrate **70**.

As described above, the membrane substrates **10** and **60** are laminated on each other via the spacer **90**. As shown in FIGS. 2 to 5, the membrane substrates **10** and **60** are laminated so that the lower surface **71** of the substrate **70** of the upper membrane board **60** faces the upper surface **21** of the substrate **20** of the lower membrane board **10**. Further, the substrate **20** of the lower membrane board **10** and the spacer **90** are bonded to each other via an adhesive layer (not shown), and the spacer **90** and the substrate **70** of the upper membrane board **60** are also bonded to each other via an adhesive layer (not shown).

As shown in FIG. 1, the connecting body **80**, the resistor **40**, and the wiring pattern **50** are included in the opening **91** in a plan view. Further, as shown in FIG. 1, in a plan view, one edge portion **80a** of the connecting body **80** overlaps with the resistor **40** over the entire area of the connecting body **80** along the X direction of the figure, and, as shown in FIG. 5, the connecting body **80** and the resistor **40** partially face each other in the cross-sectional view. Similarly, as shown in FIG. 1, in a plan view, the other edge portion **80b** of the connecting body **80** overlaps with the wiring pattern **50** over the entire area of the connecting body **80** along the X direction of the figure, and, as shown in FIG. 5, the connecting body **80** and the wiring pattern **50** partially face each other in the cross-sectional view. In one or more embodiments, as described above, a predetermined distance **D** is secured between the resistor **40** and the wiring pattern **50**. Therefore, as shown in FIG. 1, the connecting body **80** has a non-overlap region **NA** that does not overlap with the resistor **40** and the wiring pattern **50** in a plan view.

As shown in FIGS. 2 to 5, the distance is ensured between the connection body **80** and the resistor **40** by the spacer **90**, the distance is also ensured between the connecting body **80** and the wiring pattern **50** by the spacer **90**. As will be

described later, the substrate **20** of the upper membrane board **10** is deformed by pushing of the slider **100**. By this deformation, the connecting body **80** and the resistor **40** contact each other and are electrically connected to each other, and the connecting body **80** and the wiring pattern **50** contact each other and are electrically connected to each other.

In one or more embodiments, although the thickness of the spacer **90** is set so that the connecting body **80** does not contact the resistor **40** and the wiring pattern **50** at the time of non-pushing, the thickness of the spacer **90** is not particularly limited to this. The thickness of the spacer **90** may be set so that the connecting body **80** contact with the resistor **40** and the wiring pattern **50** at all times.

In one or more embodiments, “electrically connecting” the connecting body and the resistor means a state where the resistance value between the connecting body and the resistor is equal to or less than a predetermined threshold value, and does not include a state where the connecting body and the resistor only contact each other at the time of non-pushing as described above. Similarly, in one or more embodiments, “electrically connecting” the connecting body and the wiring pattern means a state where the resistance value between the connecting body and the wiring pattern is equal to or less than a predetermined threshold value, and does not include a state where the connecting body and the wiring pattern only contact each other at the time of non-pushing as described above.

The slider **100** is a member having a half-cylindrical pushing portion **110** at its tip, and is made of, for example, a metal material. As long as the slider **100** can slide while pushing the upper surface **72** of the substrate **70** of the upper membrane board **60**, the configuration of the slider **100** is not particularly limited to the above. Further, in one or more embodiments, since the object to be pushed by the slider **100** is not the resistor **40** but the upper surface **72** of the substrate **70** of the upper membrane board **60**, the slider **100** may be made of a material having electrical insulating properties such as a resin material. As will be described later, the operator's finger may be used instead of the slider **100**.

The slider **100** is movably held by the housing (not shown) or the like in which the variable resistor **1A** is housed. The slider **100** can reciprocate along the X direction (extending direction (longitudinal direction) of the connecting body **80**) while maintaining the pushing force constant in a state where the pushing portion **110** is pushed against the upper surface **72** of the substrate **70** of the upper membrane board **60** with a predetermined pushing force. In one or more embodiments, as shown in FIG. 1, in a plan view, the sliding region **SA** in which the slider **100** can slide is set between the resistor **40** and the wiring pattern **50**, is included in the non-overlap region **NA** of the connecting body **80** described above, and does not overlap with the resistor **40** and the wiring pattern **50**. The slider **100** is allowed to reciprocate along the X direction of the figure in the sliding region **SA**. The sliding region **SA** in the present embodiment corresponds to an example of the “pushing region” in one or more embodiments of the present invention.

As shown in FIG. 5, pushing of the slider **100** causes the substrate **70** of the upper membrane board **60** to bend downward, the connecting body **80** comes into contact with the resistor **40** and the wiring pattern **50** respectively, and the resistor **40** and the wiring pattern **50** are electrically connected via the connecting body **80**. Then, when the slider **100** slides while pushing the upper membrane substrate **60**, the connection position between the connecting body **80** and

11

the resistor 40 is changed, and the resistance length (resistance value) of the resistor 40 is changed.

Specifically, as described above, the power supply voltage (for example, 5 [V]) is applied to one of the wiring patterns 31 connected to the resistor 40, whereas the other wiring pattern 35 connected to the resistor 40 is grounded. Further, the wiring pattern 50 is always electrically connected to the resistor 40 via the connecting body 80 by pushing of the slider 100, and the wiring pattern 50 is electrically connected with the resistor 40 at an arbitrary position in the X direction of the figure. Therefore, the wiring pattern 50 detects a voltage (detection voltage) corresponding to the pushing position of the slider 100. That is, in one or more embodiments, the resistance value between the wiring patterns 31 and 50 is changed in accordance with the pushing position of the slider 100. A multimeter (not shown) or the like is connected to the wiring patterns 31 and 50 of the variable resistor 1A, and the multimeter or the like outputs the electric potential difference between the power supply voltage and the detection voltage of the wiring pattern 50.

For example, when the slider 100 is located at the left end of FIG. 2 in the sliding region SA, since the connection position of the connecting body 80 in the resistor 40 is also located at the left end, the wiring pattern 50 detects a voltage of substantially the same potential as the power supply voltage, and the electric potential difference (for example, 0 [V]) between the power supply voltage and the detected voltage of the wiring pattern 50 is output by a multimeter or the like.

On the other hand, as shown in FIG. 2, when the slider 100 is located substantially at the center in the sliding region SA, since the connection position of the connecting body 80 in the resistor 40 is also located substantially at the center, the wiring pattern 50 detects the voltage having a potential of substantially half of the power supply voltage, and the electric potential difference (for example, 2.5 [V]) between the power supply voltage and the detected voltage of the wiring pattern 50 is output by a multimeter or the like.

Further, when the slider 100 is located at the right end of FIG. 2 in the sliding region SA, since the connection position of the connecting body 80 in the resistor 40 is also located at the right end, the wiring pattern 50 detects a voltage of substantially the same potential as ground, and the electric potential difference (for example, 5 [V]) between the power supply voltage and the detected voltage of the wiring pattern 50 is output by a multimeter or the like.

As described above, in one or more embodiments, the connecting body 80 is disposed on the lower surface 71 of the substrate 70 of the upper membrane board 60, the slider 100 pushes the upper surface 72 of the substrate 70, and the resistor 40 and the wiring pattern 50 disposed on the upper surface 21 of the substrate 20 of the lower membrane board 10 are electrically connected via the connecting body 80 by pushing of the slider 100. That is, the substrate 70 of the upper membrane board 60 is interposed between the slider 100 and the resistor 40, and the slider 100 is not in direct contact with the resistor 40.

Further, in one or more embodiments, the sliding region SA in which the slider 100 slides is set between the resistor 40 and the wiring pattern 50 in a plan view. That is, there is not the resistor 40 immediately below the sliding region SA of the slider 100.

Therefore, in one or more embodiments, since it is possible to suppress wear of the resistor 40 due to sliding of the slider 100, it is possible to suppress the occurrence of conduction failure of the variable resistor 1A.

12

Further, in one or more embodiments, since all of the wiring patterns 31, 35, and 50 to be connected to the outside are disposed on the upper surface 21 of the same substrate 20, it is sufficient to implement a connector only on the upper surface 21, and it is possible to simplify the configuration of the variable resistor 1A.

FIG. 8 is a plan view showing the variable resistor in one or more embodiments of the present invention, FIG. 9 is a cross-sectional view showing the line IX-IX of FIG. 8, and FIG. 10 is a cross-sectional view taken along the line X-X of FIG. 8. FIG. 11 is a plan view showing the lower membrane board in one or more embodiments of the present invention, and FIG. 12 is a bottom view showing the spacer and the upper membrane board in one or more embodiments of the present invention.

As shown in FIGS. 8 to 12, although the variable resistor 1B of one or more embodiments is different from the variable resistor 1A of one or more embodiments described above in the points where (1) the spacer 90 covers the resistor 40 and the wiring pattern 50, (2) the connecting body 80 does not overlap the resistor 40 and the wiring pattern 50, and (3) the variable resistor 1B includes comb tooth patterns 45 and 55, other configurations of the variable resistor 1B are the same as one or more embodiments described above. Hereinafter, the variable resistor 1B in one or more embodiments will be described only with respect to the differences from the embodiments described above, and the same components as those in the embodiments described above will be denoted by the same reference numerals, and descriptions thereof will be omitted.

In one or more embodiments, the width of the resistor 40 is narrower as compared with in one or more embodiments described above. Further, the width of the connecting body 80 is also narrower, the entire connecting body 80 is located between the resistor 40 and the wiring pattern 50, and the entire area of the connecting body 80 is the non-overlap region NA. The width of the opening 91 of the spacer 90 is narrower than the distance D between the resistor 40 and the wiring pattern 50 (refer to FIG. 11). Therefore, the entire resistor 40 is covered with the spacer 90, and the entire first protective layer 52 of the wiring pattern 50 is also covered with the spacer 90. Further, in plan view, the connecting body 80 does not overlap with the resistor 40 and does not overlap with the wiring pattern 50. Similarly to the embodiments described above, in one or more embodiments, the sliding region SA of the slider 100 is also set between the resistor 40 and the wiring pattern 50 in a plan view, is included in the non-overlap region NA of the connecting body 80, and does not overlap with the resistor 40 and the wiring pattern 50.

Therefore, in one or more embodiments, as shown in FIG. 11, a plurality of (10 in this example) comb tooth patterns 45a to 45j and a plurality of (9 in this example) comb tooth patterns 55a to 55i are disposed on the upper surface 21 of the substrate 20 of the lower membrane board 10 in addition to the wiring patterns 31 and 35, the resistor 40, and the wiring pattern 50. In one or more embodiments, the comb tooth patterns 45a to 45j are collectively referred to as "comb tooth pattern 45", and the comb tooth patterns 55a to 55i are collectively referred to as "comb tooth pattern 55".

Similarly to the wiring patterns 31 and 35, each of the comb tooth patterns 45a to 45j and 55a to 55i is formed by printing and curing the low-resistance conductive paste. That is, each of the comb tooth patterns 45a to 45j and 55a to 55i is made of a material having the lower electrical resistivity than the electrical resistivity of the material constituting the resistor 40, and the resistance value of the

resistor 40 is sufficiently higher than the resistance value of each of the comb tooth patterns 45a to 45j and 55a to 55i to the extent that the resistance value of each of the comb tooth patterns 45a to 45j and 55a to 55i can be ignored. Specifically, the resistance value of the resistor 40 is 10 times or more with respect to the resistance value of each of the comb tooth patterns 45a to 45j and 55a to 55i, and may be 100 times or more with respect to the resistance value of each of the comb tooth patterns 45a to 45j and 55a to 55i. The electrical resistivity of the material constituting the resistor 40 is 10 times or more, and may be 100 times or more, with respect to the electrical resistivity of the material constituting each of the comb tooth patterns 45a to 45j and 55a to 55i.

The comb tooth patterns 45b to 45i in the present embodiment corresponds to an example of the "first comb tooth patterns" in one or more embodiments of the present invention, the comb tooth patterns 55a to 55i in the present embodiment corresponds to an example of the "second comb tooth patterns" in one or more embodiments of the present invention, the comb tooth patterns 45a in the present embodiment corresponds to an example of the "third comb tooth pattern" in one or more embodiments of the present invention, and the comb tooth patterns 45j in the present embodiment corresponds to an example of the "fourth comb tooth pattern" in one or more embodiments of the present invention.

As shown in FIG. 11, the comb tooth pattern 45a at the left end of the figure is branched from the wiring pattern 31 and protrudes along the Y direction of the figure. That is, the comb tooth pattern 45a is connected to the wiring pattern 31 and extends below the sliding region SA. Similarly, the comb tooth pattern 45j at the right end of the figure is branched from the wiring pattern 35 and protrudes along the Y direction of the figure. That is, the comb tooth pattern 45j is connected to the wiring pattern 35 and extends below the sliding region SA.

On the other hand, the eight comb tooth patterns 45b to 45i that are between the comb tooth patterns 45a and 45j at the both ends are electrically connected to the resistor 40 by embedding the ends of the comb tooth patterns 45b to 45i in the resistor 40. Then, these comb tooth patterns 45b to 45i protrude from the resistor 40 toward the wiring pattern 50. That is, the comb tooth patterns 45b to 45i are connected to the resistor 40 and extend below the sliding region SA. The comb tooth patterns 45a and 45j at the both ends may not be branched from the wiring patterns 31 and 35, but may be embedded in the resistor 40 in the same manner as the comb tooth patterns 45b to 45i.

Each of the comb tooth patterns 45a to 45j extends along the Y direction of the figure. The plurality of comb tooth patterns 45a to 45j are arranged substantially in parallel. Further, the plurality of comb tooth patterns 45a to 45j are arranged at substantially equal intervals.

Further, each of the comb tooth patterns 55a to 55i is branched from the first main body 51 of the wiring pattern 50, extends along the Y direction of the figure, and protrudes from the wiring pattern 50 toward the resistor 40. That is, each of the comb tooth patterns 55a to 55i is connected to the wiring pattern 50 and extends below the sliding region SA. The plurality of comb tooth patterns 55a to 55i are arranged at substantially equal intervals.

As shown in FIG. 8, all of the comb tooth patterns 45a to 45j and 55a to 55i face the connection body 80 through the opening 91 of the spacer 90 and overlap with the sliding area SA of the slider 100 in a plan view. Further, as shown in FIGS. 8 to 10, in a plan view, the comb tooth patterns 45a

to 45j and the comb tooth patterns 55a to 55i are arranged alternately along the X direction of the figure and substantially at equal intervals.

The number of comb tooth patterns 45 is not particularly limited to the above. Similarly, the number of comb tooth patterns 55 is not particularly limited to the above. Further, the arrangement of the comb tooth patterns 45 and 55 is not particularly limited to the above. As will be described later, as the number of comb tooth patterns 45 and 55 increases, the output resolution of the variable resistor 1B can be increased.

In one or more embodiments, since the width of the resistor 40 is narrow as described above, as shown in FIG. 8, the resistor 40 has a narrower width W1 than the width W2 of the pushing portion 110 of the slider 100 (W1<W2). Here, when the slider slides directly above the resistor as in the conventional technique described above, since it is necessary to widen the resistor than the pushing portion of the slider in consideration of the displacement or the like of the trajectory of the slider, it is difficult to increase the resistance. On the other hand, in one or more embodiments, since the width of the resistor 40 can be narrowed, it is possible to easily increase the resistance of the resistor 40. In one or more embodiments described above, the width of the resistor 40 may be narrower than the width of the pushing portion 110 of the slider 100.

In one or more embodiments, as shown in FIG. 9, the pushing portion 110 of the slider 100 has a dimension S1 larger than the pitch P1 of the first comb tooth patterns 45 adjacent to each other via the second comb tooth pattern 55 in the direction (X direction of the figure) in which the first and second comb tooth patterns 45 and 55 are arranged (S1>P1). Although not particularly limited, the dimension S1 of the pushing portion 110 may be 50 times or less the pitch P1 of the first comb tooth pattern 45 (S1≤10×P1).

As shown in FIGS. 9 and 10, the substrate 70 of the upper membrane board 60 is bent downward due to pushing of the slider 100, and the connecting body 80 contact the comb tooth patterns 45 and 55 adjacent to each other. Therefore, the resistor 40 and the wiring pattern 50 are electrically connected via the connecting body 80. Specifically, in the state shown in FIG. 9, the comb tooth patterns 45f of the comb tooth patterns 45a to 45j and the comb tooth patterns 55e of the comb tooth patterns 55a to 55i are electrically connected to each other via the connecting body 80.

The number of comb tooth patterns 45a to 45j simultaneously connected to the connecting body 80 by pushing of the slider 100 may be plural. Similarly, the number of comb tooth patterns 55a to 55i simultaneously connected to the connecting body 80 by pushing of the slider 100 may be plural.

In one or more embodiments, as the slider 100 slides while pushing the upper membrane board 60, the combination of the comb tooth patterns 45 and 55 connected via the connecting body 80 is changed sequentially, and the resistance length (resistance value) of the resistor 40 is changed.

For example, in the state shown in FIG. 9, as described above, the comb tooth patterns 55e and 45f are connected via the connecting body 80. As the slider 100 slides in the +X direction of the figure from this state, the combinations of comb tooth patterns connected via the connecting body 80 is changed to the comb tooth patterns 55e and 45f the comb tooth patterns 45f and 55f the comb tooth patterns 55f and 45g the comb tooth patterns 45g and 55g the comb tooth patterns 55g and 45h the comb tooth patterns 45i and 55i the comb tooth patterns 55i and 45j.

15

Along with this, the wiring pattern **50** connected to the comb tooth patterns **55a** to **55i** detects a voltage (detection voltage) corresponding to the combination of the comb tooth patterns **45** and **55** connected via the connecting body **80**. That is, also in one or more embodiments, the resistance value between the wiring patterns **31** and **50** is changed in accordance with the pushing position of the slider **100**. When the slider **100** slides in the +X direction of the figure, the resistance value between the wiring patterns **31** and **50** gradually increases as the slider **100** slides. A multimeter or the like is connected to the wiring patterns **31** and **50** of the variable resistor **1B**, and the multimeter or the like outputs the electric potential difference between the power supply voltage and the detection voltage of the wiring pattern **50**.

On the other hand, as the slider **100** slides in the -X direction of the figure from the state shown in FIG. 9, the combinations of comb tooth patterns connected via the connecting body **80** is changed to the comb tooth patterns **45f** and **55e** the comb tooth patterns **55e** and **45e** the comb tooth patterns **45e** and **55d** the comb tooth patterns **55d** and **45d** the comb tooth patterns **45d** and **55c** the comb tooth patterns **45b** and **55a** the comb tooth patterns **55a** and **45a**. In this case, the resistance value between the wiring patterns **31** and **50** gradually decreases as the slider **100** slides.

For example, when the comb tooth patterns **45a** and **55a** that are the leftmost combination of FIG. 9 are connected via the connecting body **80**, the wiring pattern **50** detects a voltage of substantially the same potential as the power supply voltage, and the multimeter or the like outputs the electric potential difference (for example, 0 [V]) between the power supply voltage and the detected voltage of the wiring pattern **50**.

On the other hand, as shown in FIG. 9, when the comb tooth patterns **55e** and **45f** that are substantially central combinations are connected via the connecting body **80**, the wiring pattern **50** detects the voltage having a potential of substantially half of the power supply voltage, and the multimeter or the like outputs the electric potential difference (for example, 2.5 [V]) between the power supply voltage and the detected voltage of the wiring pattern **50**.

Further, when the comb tooth patterns **55i** and **45j** that are the rightmost combination of FIG. 9 are connected via the connecting body **80**, the wiring pattern **50** detects a voltage of substantially the same potential as ground, and the multimeter or the like outputs the electric potential difference (for example, 5 [V]) between the power supply voltage and the detected voltage of the wiring pattern **50**.

Thus, in one or more embodiments, since the resistance value between the wiring patterns **31** and **50** is changed in accordance with the combination of the comb tooth patterns **45** and **55** connected via the connecting body **80**, the output of the variable resistor **1B** has a stepped shape. Therefore, as the number of comb patterns **45** and **55** is increased and the pitch of the comb pattern **45** and **55** is narrower, the resolution of the output of the variable resistor **1B** can be heightened.

As described above, in one or more embodiments, the connecting body **80** is disposed on the lower surface **71** of the substrate **70** of the upper membrane board **60**, the slider **100** pushes the upper surface **72** of the substrate **70**, and the resistor **40** and the wiring pattern **50** respectively connected to the comb tooth patterns **45** and **55** are electrically connected by connecting the comb tooth patterns **45** and **55** via the connecting body **80**. That is, the substrate **70** of the upper membrane board **60** is interposed between the slider **100** and the resistor **40**, and the slider **100** does not directly contact the resistor **40**.

16

Further, in one or more embodiments, the sliding region **SA** in which the slider **100** slides is set between the resistor **40** and the wiring pattern **50** in a plan view. That is, there is no resistor **40** immediately below the sliding region **SA** of the slider **100**.

Therefore, in one or more embodiments, since it is possible to suppress wear of the resistor **40** due to sliding of the slider **100**, it is possible to suppress the occurrence of conduction failure of the variable resistor **1B**.

Further, in one or more embodiments, the comb tooth patterns **45b** to **45i** protruding from the resistor **40** contact the connecting body **80**, and the resistor **40** itself does not directly contact the connecting body **80**. Further, in one or more embodiments, the entire area of the resistor **40** is covered with the spacer **90** and is protected by the spacer **90**. Therefore, in one or more embodiments, wear of the resistor **40** does not occur in the first place.

Further, in one or more embodiments, the sliding region **SA** of the slider **100** overlaps with the comb tooth patterns **45b** to **45i** protruding from the resistor **40**, and the sliding region **SA** does not overlap with the resistor **40** itself. Therefore, since the sliding region **SA** of the slider **100** is not limited by the thick end portion of the resistor **40** due to the overlap with the wiring patterns **31** and **35**, it is possible to use the entire area of the resistor **40** as a detectable range of the variable resistor **1B**.

Further, in one or more embodiments, the leftmost comb tooth pattern **45a** of FIG. 9 is connected to one wiring pattern **31**, and the rightmost comb tooth pattern **45j** of FIG. 9 is connected to the other wiring pattern **35**. Therefore, the maximum value of the output of the variable resistor **1B** can be made equal to the power supply voltage, and the minimum value of the output of the variable resistor **1B** can be made equal to the ground.

Further, similarly to embodiments described above, in one or more embodiments, since all of the wiring patterns **31**, **35**, and **50** to be connected to the outside are disposed on the upper surface **21** of the same substrate **20**, it is sufficient to implement a connector only on the upper surface **21**, and it is possible to simplify the configuration of the variable resistor **1B**.

Embodiments heretofore explained are described to facilitate understanding of the present invention and are not described to limit the present invention.

For example, the configuration of one or more embodiments described above may be combined.

Specifically, as in the variable resistor **1C** shown in FIG. 13, similarly to embodiments described above, the comb tooth patterns **45** may be projected from the resistor **40** to overlap the connection body **80** with the comb tooth patterns **45**, and the other edge **80b** of the connecting body **80** may overlap with the wiring pattern **50**, similarly to one or more embodiments described above. FIG. 13 is a plan view showing the variable resistor in one or more embodiments of the present invention.

Also in this case, similarly to one or more embodiments described above, the resistor **40** itself does not contact the connection **80**, and the entire area of the resistor **40** is protected by the spacer **90**. Therefore, since wear of the resistor **40** due to sliding of the slider **100** does not occur in the first place, it is possible to suppress the occurrence of conduction failure of the variable resistor **1C**.

Alternatively, as in the variable resistor **1D** shown in FIGS. 14 to 16, the wiring pattern **50** may be disposed on the upper substrate **70** and may be directly connected to the connecting body **80**. FIG. 14 is a plan view showing the variable resistor in one or more embodiments of the present

invention, FIG. 15 is a cross-sectional view taken along the line XV-XV of FIG. 14, and FIG. 16 is a bottom view illustrating the spacer and the upper membrane board in one or more embodiments of the present invention.

Specifically, the variable resistor 1D shown in FIGS. 14 to 16 is different from the above-mentioned variable resistor 1C shown in FIG. 13 in the points where, instead of forming the wiring pattern 50 on the upper surface 21 of the lower substrate 20, the wiring pattern 50 is formed on the lower surface 72 of the upper substrate 70 and the wiring pattern 50 is directly connected to the connecting body 80. In this case, as shown in FIG. 16, the wiring pattern 50 includes the first main body 51 only, and the first main body 51 is connected to the second main body 81 of the connecting body 80.

In one or more embodiments, as shown in FIG. 14, the pushing portion 110 of the slider 100 has a dimension 51 larger than the pitch P1 of the first comb tooth patterns 45 adjacent to each other in the direction (X direction of the figure) in which the first comb tooth patterns 45 are arranged (S1>P1). Although not particularly limited, the dimension 51 of the pushing portion 110 may be 50 times or less the pitch P1 of the first comb tooth pattern 45 (S1≤10×P1).

Alternatively, as in the variable resistor 1E shown in FIG. 17, the resistor 40 may be covered with a resin layer 95 different from the spacer 90. FIG. 17 is a plan view showing the variable resistor in one or more embodiments of the present invention.

Specifically, the variable resistor 1E shown in FIG. 17 is different from the above-mentioned variable resistor 1C shown in FIG. 13 in the points where, instead of covering the resistor 40 with the spacer 90, the opening 91 of the spacer 90 has a size that does not include the resistor 40 and the resistor 40 is covered with a resin layer 95 such as a resist in order to protect the resistor 40. The spacer 90 may partially cover the resistor 40 and the resin layer 93 may partially cover the resistor 40, thereby the spacer 90 and the resin layer 95 may cover the entire resistor 40.

In one or more embodiments described above, although the comb tooth patterns 45 and 55 are disposed between the resistor 40 and the wiring pattern 50, the arrangement of the comb tooth patterns 45 and 55 is not particularly limited thereto. For example, the connection body 80 may be disposed at a position away from the resistor 40 and the wiring pattern 50 without disposing the connection body 80 between the resistor 40 and the wiring pattern 50, and the comb teeth patterns 45 and 55 may be led out to below the connecting body 80.

Further, in one or more embodiments described above, although, regarding the operation of the slider 100, it is described that the slider 100 that contacts and pushes the upper surface 72 of the upper membrane board 60 slides (reciprocates) along the X direction of the figure, the operation of the slider 100 is not particularly limited thereto.

For example, the slider 100 may repeat the operation of pushing rising horizontal moving pushing rising horizontal moving. Specifically, it may be repeated the operation where the slider 100 contacts and pushes one point on the upper surface 72 of the upper membrane board 60, then rises without sliding on the upper surface 72, then horizontally moves in the X direction (extending direction (longitudinal direction) of the connecting body 80) of the figure, and then contacts and pushes the other point on the upper surface 72 of the upper membrane board 60. Also in this case, the resistance length of the resistor 40 (resistance value) is

changed in accordance with pushing of the slider 100 at different points, and different voltages is output from the wiring pattern 50.

In one or more embodiments described above, although the operation of the variable resistor 1A' was performed by the slider 110 included in the variable resistor 1A~1E itself, the operation of the variable resistor is not particularly limited thereto. For example, instead of the slider 100, an operator may operate the variable resistor by a finger.

In one or more embodiments, although the resistance value of the variable resistor 1A~1E is detected by connecting the wiring pattern 31 to the power supply, connecting the wiring pattern 35 to ground, and acquiring the detected voltage of the wiring pattern 50, the circuit configuration for detecting the resistance value of the variable resistor is not particularly limited thereto.

For example, the power supply may be connected to the wiring patterns 31 and 50 without providing the wiring pattern 35. Also in this case, the resistance value between the wiring patterns 31 and 50 is changed in accordance with the pushing position of the slider 100.

Although the disclosure has been described with respect to only a limited number of embodiments, those skilled in the art, having benefit of this disclosure, will appreciate that various other embodiments may be devised without departing from the scope of the present invention. Accordingly, the scope of the invention should be limited only by the attached claims.

- The invention claimed is:
- 1. A variable resistor, comprising:
a first substrate having a first main surface;
a resistor disposed on the first main surface;

19

a first wiring pattern disposed on the first main surface and connected to the resistor;
 a spacer having an opening;
 a second substrate that:
   has second and third main surfaces, and
   is disposed on the first substrate via the spacer such that the second main surface is opposed to the first main surface;
 a connecting body that is:
   disposed on the second main surface such that the connecting body is disposed in the opening, and configured to electrically connect to the resistor by pushing of a pusher from the third main surface; and a second wiring pattern that is either:
   disposed on the first main surface and configured to be electrically connected to the connecting body by the pushing of the pusher; or
   disposed on the second main surface and connected to the connecting body, wherein
   in a plan view, the connecting body has a non-overlap region that does not overlap with the resistor,
   in a plan view, a pushing region in which the pusher can push is included in the non-overlap region, and a resistance value between the first wiring pattern and the second wiring pattern is changed based on a pushing position of the pusher,
   in a plan view, the connecting body partially overlaps with the resistor,
   in a plan view, the pushing region does not overlap with the resistor, and
   the connecting body contacts the resistor by the pushing of the pusher from the third main surface.

2. A variable resistor, comprising:

a first substrate having a first main surface;
 a resistor disposed on the first main surface;
 a first wiring pattern disposed on the first main surface and connected to the resistor;
 a spacer having an opening;
 a second substrate that:
   has second and third main surfaces, and
   is disposed on the first substrate via the spacer such that the second main surface is opposed to the first main surface;
 a connecting body that is:
   disposed on the second main surface such that the connecting body is disposed in the opening, and configured to electrically connect to the resistor by pushing of a pusher from the third main surface; and a second wiring pattern that is either:
   disposed on the first main surface and configured to be electrically connected to the connecting body by the pushing of the pusher; or
   disposed on the second main surface and connected to the connecting body, wherein
   in a plan view, the connecting body has a non-overlap region that does not overlap with the resistor,
   in a plan view, a pushing region in which the pusher can push is included in the non-overlap region, and a resistance value between the first wiring pattern and the second wiring pattern is changed based on a pushing position of the pusher,
   the variable resistor further comprises first comb tooth patterns disposed on the first main surface and connected to the resistor,
   in plan view, the first comb tooth patterns overlap with the pushing region,

20

a material of which the resistor is made has an electrical resistivity higher than an electrical resistivity of a material of which the first comb tooth patterns are made,
 the second wiring pattern is disposed on the first main surface,
 the variable resistor further comprises second comb tooth patterns disposed on the first main surface and connected to the second wiring pattern,
 in a plan view, the second comb tooth patterns overlap with the pushing region,
 a material of which the resistor is made has an electrical resistivity higher than an electrical resistivity of a material of which the second comb tooth patterns are made, and
 the connecting body contacts the first comb tooth pattern and the second comb tooth pattern by the pushing of the pusher from the third main surface.

3. The variable resistor according to claim 2, wherein the first comb tooth patterns and the second comb tooth patterns are arranged alternately and substantially at equal intervals along an extending direction of the connecting body in the pushing region, and a pushing portion of the pusher that contacts the third surface has a dimension larger than a pitch of the first comb tooth patterns adjacent to each other via the second comb tooth pattern in a direction in which the first and second comb tooth patterns are arranged.

4. A variable resistor, comprising:

a first substrate having a first main surface;
 a resistor disposed on the first main surface;
 a first wiring pattern disposed on the first main surface and connected to the resistor;
 a spacer having an opening;
 a second substrate that:
   has second and third main surfaces, and
   is disposed on the first substrate via the spacer such that the second main surface is opposed to the first main surface;
 a connecting body that is:
   disposed on the second main surface such that the connecting body is disposed in the opening, and configured to electrically connect to the resistor by pushing of a pusher from the third main surface; and a second wiring pattern that is either:
   disposed on the first main surface and configured to be electrically connected to the connecting body by the pushing of the pusher; or
   disposed on the second main surface and connected to the connecting body, wherein
   in a plan view, the connecting body has a non-overlap region that does not overlap with the resistor,
   in a plan view, a pushing region in which the pusher can push is included in the non-overlap region, and a resistance value between the first wiring pattern and the second wiring pattern is changed based on a pushing position of the pusher,
   the variable resistor further comprises first comb tooth patterns disposed on the first main surface and connected to the resistor,
   in plan view, the first comb tooth patterns overlap with the pushing region,
   a material of which the resistor is made has an electrical resistivity higher than an electrical resistivity of a material of which the first comb tooth patterns are made,

21

the second wiring pattern is disposed on the first main surface, in plan view, the connecting body partially overlaps with the second wiring pattern, and the connecting body contacts the first comb tooth patterns and the second wiring pattern by the pushing of the pusher from the third main surface.

5. The variable resistor according to claim 4, wherein the first comb tooth patterns are arranged substantially at equal intervals along an extending direction of the connecting body in the pushing region, and a pushing portion of the pusher that contacts the third surface has a dimension larger than a pitch of the first comb tooth patterns adjacent to each other in a direction in which the first comb tooth patterns are arranged.

6. A variable resistor, comprising: a first substrate having a first main surface; a resistor disposed on the first main surface; a first wiring pattern disposed on the first main surface and connected to the resistor; a spacer having an opening; a second substrate that:

has second and third main surfaces, and is disposed on the first substrate via the spacer such that the second main surface is opposed to the first main surface; a connecting body that is:

disposed on the second main surface such that the connecting body is disposed in the opening, and configured to electrically connect to the resistor by pushing of a pusher from the third main surface; and a second wiring pattern that is either:

disposed on the first main surface and configured to be electrically connected to the connecting body by the pushing of the pusher; or

disposed on the second main surface and connected to the connecting body, wherein

in a plan view, the connecting body has a non-overlap region that does not overlap with the resistor, in a plan view, a pushing region in which the pusher can push is included in the non-overlap region,

a resistance value between the first wiring pattern and the second wiring pattern is changed based on a pushing position of the pusher,

the variable resistor further comprises first comb tooth patterns disposed on the first main surface and connected to the resistor,

in plan view, the first comb tooth patterns overlap with the pushing region,

a material of which the resistor is made has an electrical resistivity higher than an electrical resistivity of a material of which the first comb tooth patterns are made,

the variable resistor further comprises: a third wiring pattern connected to the resistor; a third comb tooth pattern connected to the first wiring pattern; and a fourth comb tooth pattern connected to the third wiring pattern, and

in a plan view, the third and fourth comb tooth patterns overlap with the pushing region.

7. The variable resistor according to claim 2, wherein the spacer covers the whole resistor.

8. A variable resistor, comprising: a first substrate having a first main surface; a resistor disposed on the first main surface;

22

a first wiring pattern disposed on the first main surface and connected to the resistor; a spacer having an opening; a second substrate that:

has second and third main surfaces, and is disposed on the first substrate via the spacer such that the second main surface is opposed to the first main surface;

a connecting body that is:

disposed on the second main surface such that the connecting body is disposed in the opening, and configured to electrically connect to the resistor by pushing of a pusher from the third main surface; and a second wiring pattern that is either:

disposed on the first main surface and configured to be electrically connected to the connecting body by the pushing of the pusher; or

disposed on the second main surface and connected to the connecting body, wherein

in a plan view, the connecting body has a non-overlap region that does not overlap with the resistor, in a plan view, a pushing region in which the pusher can push is included in the non-overlap region,

a resistance value between the first wiring pattern and the second wiring pattern is changed based on a pushing position of the pusher,

the variable resistor further comprises first comb tooth patterns disposed on the first main surface and connected to the resistor,

in plan view, the first comb tooth patterns overlap with the pushing region,

a material of which the resistor is made has an electrical resistivity higher than an electrical resistivity of a material of which the first comb tooth patterns are made,

the variable resistor further comprises a resin layer covering at least a part of the resistor, and at least one of the resin layer and the spacer covers the whole resistor.

9. The variable resistor according to claim 2, wherein the resistor has a width narrower than a width of a pushing portion of the pusher that contacts the third main surface.

10. A variable resistor, comprising: a first substrate having a first main surface; a resistor disposed on the first main surface; a first wiring pattern disposed on the first main surface and connected to the resistor; a spacer having an opening; a second substrate that:

has second and third main surfaces, and is disposed on the first substrate via the spacer such that the second main surface is opposed to the first main surface;

a connecting body that is:

disposed on the second main surface such that the connecting body is disposed in the opening, and configured to electrically connect to the resistor by pushing of a pusher from the third main surface; and a second wiring pattern that is either:

disposed on the first main surface and configured to be electrically connected to the connecting body by the pushing of the pusher; or

disposed on the second main surface and connected to the connecting body, wherein in a plan view, the connecting body has a non-overlap region that does not overlap with the resistor,

in a plan view, a pushing region in which the pusher can push is included in the non-overlap region, a resistance value between the first wiring pattern and the second wiring pattern is changed based on a pushing position of the pusher,
5 the variable resistor further comprises first comb tooth patterns disposed on the first main surface and connected to the resistor, in plan view, the first comb tooth patterns overlap with the pushing region,
10 a material of which the resistor is made has an electrical resistivity higher than an electrical resistivity of a material of which the first comb tooth patterns are made, the second wiring pattern is disposed on the second main 15 surface and is connected to the connecting body, the connecting body contacts the first comb tooth pattern by the pushing of the pusher from the third main surface, the first comb tooth patterns are arranged substantially at 20 equal intervals along an extending direction of the connecting body in the pushing region, and a pushing portion of the pusher that contacts the third surface has a dimension larger than a pitch of the first comb tooth patterns adjacent to each other in a direction 25 in which the first comb tooth patterns are arranged.
